UNITED STATES PATENT OFFICE.

GLOVER EDWIN RUCKSTELL, OF BERKELEY, CALIFORNIA.

INTERNAL-COMBUSTION ENGINE.

Application filed January 18, 1922. Serial No. 530,039.

This invention relates to internal combustion engines, and more especially to high speed engines of the explosive type.

The object of the invention is to increase the volumetric efficiency of such engines. The quantity of charge drawn into the cylinder is always less than the theoretical quantity which would fill the working volume of the cylinder at atmospheric pressure and temperature and the ratio of the actual to the theoretical is called the volumetric efficiency. The aim of all designers of high speed engines is for a high volumetric efficiency, and one way of accomplishing this is to ram an excess charge into the combustion chamber. Designers of racing car engines obtain this rammed charge by arranging the firing order of the cylinders so as to benefit to the greatest extent by the velocity or rate of flow of the gases in the manifold. For instance, in a four-cylinder engine using a single intake manifold and having a firing order of one-three-four-two, it will be seen that at the time No. 1 opens to receive a charge the gases in the manifold are moving at high velocity in the direction of No. 1 on account of having just been acted upon by cylinder No. 2, and, similarly, when cylinder No. 4 takes in a charge, gases are flowing in its direction by reason of the preceding induction stroke of cylinder No. 3. In racing car engines the rate of flow of these gases through the manifold is in excess of 250 feet per second, and, since the mixture of fuel and air possesses weight, it follows that considerable inertia or head will be present when the gases reach the ends of the manifold adjacent cylinders Nos. 1 and 4.

The effect of this will be to ram an excess charge into these end cylinders. However, this plan fails to take into account the loss of compression pressure occurring in cylinders Nos. 2 and 3 which results from the duty imposed upon these cylinders of overcoming the inertia and reversing the direction of flow of these rapidly moving gases in the manifold. Thus, when cylinder No. 3 starts its induction stroke, cylinder No. 1 has just finished and the gases are then piled up in the opposite end of the manifold. Similarly, when No. 2 starts its induction stroke No. 4 has just closed and the gases are piled up in the other end of the manifold. As already stated, these gases possess inertia and that inertia must not only be

overcome by cylinders Nos. 2 and 3, but, in addition, a complete reversal in the direction of flow of the gases must be brought about by these cylinders. The effect thus produced upon cylinders Nos. 2 and 3 is analogous to that of a cylinder running on a partially closed throttle. To get the maximum efficiency out of the engine the compression pressures in all the cylinders should be approximately equal. The present invention contemplates the equalizing of these pressures in all cylinders without losing the effect of the rammed charges.

One method of accomplishing this is set forth in the following description and illustrated in the accompanying drawing, in which—

Fig. 1 shows a diagram of a conventional type of four-cylinder engine and manifold connections therefor.

Fig. 2 shows a diagram illustrating in vertical cross section an arrangement of cylinders suitable for accomplishing the object of this invention.

Fig. 3 shows a modified form of the invention using two carburetors for a four-cylinder engine.

Referring to the arrangement shown in Fig. 1, the cylinders of a conventional type of engine are designated in successive order by the numerals 1, 2, 3 and 4, and an intake manifold is shown at 10. Assuming the firing orders of these cylinders to be 1-3-4-2, it will be seen that after cylinder No. 1 has taken in its charge the gases are piled up in the neighborhood of its intake at one end of the manifold. Cylinder No. 3 following with its suction stroke must overcome the inertia of these gases and reverse the direction of their flow. Keeping in mind the fact that the engine is operating at high speed and that the gases possess an appreciable weight, it will be seen that cylinder No. 3 will receive a rarefied charge. The period of induction in a high speed engine is very small, and, in the space of time allotted, the inertia of these gases cannot be overcome. Cylinder No. 4, however, being adjacent cylinder No. 3 will open at a time to receive the benefit of the velocity and direction of flow of the gases initiated by cylinder No. 3, and the result will be a piling up of the gases at the intake of cylinder No. 4, thereby producing a rammed charge in the last-named cylinder. Cylinder No. 2 now opens to a condition where the

gases in the manifold are piled up in the opposite end and it therefore is handicapped to the same extent as cylinder No. 3. The movement of gases initiated by cylinder No. 5 2 will, however, benefit cylinder No. 1. The same alternating high and low charges occur in any other usual firing order, such as 1-2-4-3, in which case cylinders Nos. 2 and 10 3 will receive rammed charges and the cylinders Nos. 1 and 4 reduced charges.

Thus, it can be seen that if the compression space in all cylinders be equal, the compression ratio and the mean effective pressure of those cylinders receiving reduced charges will be comparatively low, whereas the compression ratio and the mean effective pressure of those cylinders receiving rammed charges will be much higher. It is well known that the mean effective pressure throughout the piston stroke and the efficiency of the power charge are dependent upon the compression ratio.

These unequal compression pressures mean that two cylinders are giving maximum efficiency and the other two are not. To overcome this I reduce the clearance volume of those cylinders receiving reduced charges to an extent sufficient to raise their compression pressures to the equal of the other cylinders. This may be accomplished, as shown in Fig. 2, by employing pistons 11 of one length in cylinders firing alternately and pistons 12 of a different length in cylinders firing intermediately, thus giving less clearance volume in the cylinders which, on account of their position and firing order, do not receive rammed charges.

Other ways of accomplishing this result will readily suggest themselves to those skilled in the art. For instance, a reduction in the compression space in the cylinders

receiving reduced charges can be brought about by forming a smaller core in the heads of those cylinders or by giving the pistons therein a longer stroke than the pistons of 45 the remaining cylinders.

In Fig. 3 each pair of cylinders has its own carburetor. An intake manifold 13 is used for cylinders 1 and 2 and a separate manifold 14 for the cylinders 3 and 4. In 50 this form, and assuming a firing order of 1-3-4-2, it will be seen that No. 1 will open for induction immediately following the suction stroke of No. 2. The flow of gas thus started from the carburetor by No. 55 2 will ram cylinder No. 1. Likewise cylinder No. 4 will be charged by the gases started by No. 3. However, cylinder No. 2 will open for intake so long after the suction stroke of No. 1 that the gases in the 60 manifold will not be in motion, and, therefore, part of the effect of the suction stroke in No. 2 will be lost in starting the gases in motion through the manifold. The same is true of cylinder No. 3.

Having thus described my invention, what I claim and desire to secure by Letters Patent is:

A high speed engine of the four-stroke cycle type including multiple cylinders and 70 a single intake manifold for adjacent cylinders, the cylinders which have to overcome the inertia of the flow of gases in the manifold by reason of their position and firing order having less clearance volume, 75 and those which, on account of their position and firing order, are assisted by the inertia of the gases in the manifold created by the induction strokes of the other cylinders having greater clearance volume.
